UNITED STATES PATENT OFFICE.

CHARLES Y. KNIGHT, OF PASADENA, CALIFORNIA, ASSIGNOR TO THE KNIGHT AMERICAN PATENTS COMPANY, OF CHICAGO, ILLINOIS, A CORPORATION OF ILLINOIS.

MECHANISM FOR FACILITATING THE STARTING OF INTERNAL-COMBUSTION ENGINES.

1,305,905.

Specification of Letters Patent. Patented June 3, 1919.

Application filed October 17, 1918. Serial No. 258,527.

To all whom it may concern:

Be it known that I, CHARLES Y. KNIGHT, a citizen of the United States, residing at Pasadena, in the county of Los Angeles and

5 State of California, have invented certain new and useful Improvements in Mechanism for Facilitating the Starting of Internal-Combustion Engines, of which the following is a specification.

10 This invention has for its object the provision of mechanism of the class named which shall be of improved construction and operation.

The invention is exemplified in the combination and arrangement of parts shown in the accompanying drawings, and described in the following specification, and it is more particularly pointed out in the appended claims.

20 In the drawings—

Figure 1 is a side elevation of one form of engine showing one embodiment of the present invention applied thereto.

Fig. 2 is a vertical section on line 2—2 of 25 Fig. 1, and

Fig. 3 is a fragmentary vertical section on line 3—3 of Fig. 1.

In many cases the conditions under which internal combustion engines are operated, 30 makes it imperative that the weight of the engine and associated parts shall be reduced to a minimum and under such conditions it is very desirable to dispense with the usual starting mechanism. This is especially true

35 in aerial navigation and this renders the starting of the engine very difficult unless special provision is made for this purpose.

In my copending application, Serial No. 242,278, filed June 27, 1918, I have shown

40 one form of internal combustion engine in which the engine cylinders and base rotate independently of the crank shaft and at different rates of speed and in the drawings in the present application I have illustrated my

45 invention as applied to an engine of this type. In the drawings, the numeral 10 designates the base or crank casing of an internal combustion engine provided with radially arranged cylinders 11. The casing 10

50 is provided with a hollow journal 12 supported in a bearing 13 which is carried by a frame member 14 of the machine operated by the engine. At the side of the casing 10

opposite the bearing 13 a second bearing 15 is supported by the frame 16 and has journaled therein a projection 17 which extends from the casing 10. In this way the casing 10 and the engine cylinders 11 are mounted to rotate freely in the frame members 14 and 15 of the machine operated by the engine. 60 The crank shaft 18 extends through the hollow projections 12 and 17 of the casing 10 and is journaled to rotate therein. One end of the shaft 18 is connected with the load to be driven which in the drawing is illustrated 65 as a propeller blade 19 of an aeroplane. The opposite end of the crank shaft 18 is provided with a gear 20 loose upon the shaft 18 but arranged to be caused to rotate therewith by a friction clutch 21. The clutch 21 70 is operated by a lever 22 connected with the clutch by suitable links and held in its various positions of adjustment by a ratchet 23. A spring 24 may be provided to normally force the clutch into position to lock the gear 75 20 with the shaft 18. The gear 20 meshes with a larger gear 24 which is formed integral with a pinion 25 meshing with an idler pinion 26 which in turn drives a second large gear 27. The gear 27 is rigid with a 80 shaft 28 journaled in a sleeve 29 upon the frame 16 of the machine and the shaft 28 carries a sprocket 29 which drives a sprocket chain 30. The sprocket chain 30 passes around a sprocket wheel 31 formed integral 85 with the engine casing 10.

When the engine is operated the shaft 18 and casing 10 will, of course, be rotated relative to one another and the chain of gearing driven by the pinion 20 on the shaft 18 determines the relative speed of rotation of the two engine parts upon the frame 16. It will be seen that the casing 10 will be rotated through the reduction gearing at a comparatively low speed while the shaft 18 and the propeller blade 19 will be driven at a rapid rate of speed in an opposite direction. By this arrangement the advantages of a rotating engine base and cylinders are secured without the disadvantages resulting from 100 the rapid speed of rotation incident to the type of engine in which the cylinder base rotates at the rate of speed of the driven parts.

As shown in Figs. 1 and 3, the end of the 105 shaft 18 has rigidly secured thereto a ratchet

- 2
- wheel 32 and a pawl 33 is pivoted on the frame 16 and is provided with a hand lever 34 by which it may be moved into and out of engagement with the ratchet wheel.
- 5 In starting an engine of this type, the clutch 21 is disconnected and the pawl 33 is moved out of engagement with the ratchet 32. This leaves the engine casing 10 and the shaft 18 free to be rotated in unison with
- 10 one another and consequently the entire mass may be rotated as a free wheel without shifting the pistons in their cylinders and consequently without the resistance due to compression in the cylinders. This makes
- 15 it comparatively easy to bring the speed of rotation of the engine base up to a point where the moving parts will possess considerable energy because of their momentum. The parts will be rotated in a counter-
- 20 clockwise direction, as viewed in Figs. 2 and 3. When the momentum of the moving parts has become sufficiently great, the operator will move the pawl 33 into engagement with the ratchet 32 and thus stop the rotation of the shaft 18 leaving the casing 10 free to continue its rotation in a counter-clockwise direction. This of course will cause relative rotation between the crank shaft and engine base and a consequent
- 25 movement of the pistons in their cylinders exactly the same as if the engine base were held stationary and the engine cranked in the usual manner in starting. It will be noted that when the shaft 18 is brought to
- 30 a stop the two relatively movable parts of the engine will be rotating in the same direction relative to one another that they assume during the operation of the engine and consequently as soon as the explosions in
- 35 the cylinders begin, the parts will continue to rotate in the same direction relative to one another but the relative rotation will be kept up by the energy of the explosions in the cylinders. The clutch 21 may now be
- 40 thrown in so that the engine frame and shaft may be brought to their proper speed of rotation relative to the machine frame, and when this has been accomplished the engine will be operating in a normal way.
- 45 When the explosions begin in the engine cylinder the tendency will be to rotate the shaft 18 in a clockwise direction, as viewed in Fig. 3, and the heavy parts, including the engine frame and cylinder casings, in a
- 50 counter-clockwise direction. As these heavy parts are already moving in this direction, there will be no sudden strain brought upon the engine but the heavy parts will continue to move in the same direction in which they
- 55 are already going. There will be no great resistance to the movement of the shaft in the direction in which it is rotated because it rotates freely under the pawl 33 in this direction.
- 60 65 It will be apparent that instead of bringing the shaft 18 to a sudden stop by throwing the pawl 33 into engagement with the ratchet 32, the engine may be started by first bringing the heavy parts 10 and 11 up to the necessary speed to give them the required momentum and then throwing the clutch 21 into engagement with the gear 20 which will produce relative rotation of the shaft 18 and engine cylinders 11 in a forward direction and cause explosions to occur in the cylinders in the same way as if the engine were cranked in the usual manner.
- I claim:
1. In combination, a motor mounted to rotate and having a shaft arranged to be driven thereby, means for preventing rotation of said shaft while other parts of said motor continue to rotate to cause relative movement of said shaft and rotating parts for the purpose of starting the operation of said motor.
2. In combination, a motor having the frame member thereof mounted for rotation and having a crank shaft arranged to rotate relative to said frame during the operation of said motor, means for supporting said frame and shaft to rotate in unison with one another, and means for stopping the rotation of said shaft to cause relative rotation of said frame and shaft for the purpose of starting the operation of said motor.
3. In an internal combustion engine, an engine base having engine cylinders mounted thereon, means for supporting said base and cylinders so that they are free to rotate, a shaft connected with said cylinders to be driven thereby, means for supporting said shaft so that it is free to rotate with said engine base and cylinders, and means for checking the rotation of said shaft to cause relative movement between said base and shaft for the purpose of starting the operation of said motor.
4. An internal combustion engine having a rotary crank shaft, cylinders arranged to rotate about said crank shaft, means for supporting said shaft and cylinders so that they are free to rotate in unison with one another, and means for holding said shaft to cause it to rotate relative to said cylinders for the purpose of starting the operation of said engine.
5. The combination with an internal combustion engine having cylinders and a crank shaft both arranged to rotate, of means for supporting said cylinders and crank shaft so that they are free to rotate in unison with one another, and means for causing said cylinders and shaft to rotate relatively to one another.
6. An internal combustion engine comprising a base having cylinders and auxiliary mechanism connected therewith, a rotary crank shaft driven by said cylinders, speed reduction gearing driven by said crank shaft

- for rotating said base, cylinders and auxiliary mechanism carried thereby, and means for disconnecting said speed reduction gearing to permit said base and crank shaft to 5 rotate in unison with one another.
7. In an internal combustion engine, driving mechanism and a driven member, means for supporting said driving mechanism and driven member to move in unison with one 10 another to develop kinetic energy in said moving parts, and means for causing said parts to move relative to one another under the influence of the energy thus developed for the purpose of starting the operation of 15 said engine.
8. In an internal combustion engine, a base member having cylinders connected therewith, a crank shaft journaled to rotate in said base member and driven by said engine, bearings for supporting said base member and shaft so that they are free to rotate 20 in unison with one another to develop energy of rotation, and means for checking the rotation of said shaft while said engine base continues to move thus producing relative rotation 25 between said shaft and engine base for the purpose of starting the operation of said engine.
9. In an internal combustion engine, a base having cylinders carried thereby, a crank shaft journaled in said base and driven by said cylinders, means for supporting said base and shaft so that they are free to rotate in unison with one another, means 30 for connecting said shaft and base to cause them to rotate relative to one another, and means for throwing said connecting means into and out of operative relation with said engine base and shaft.
10. In combination, an engine comprising a driving portion and a driven portion adapted for relative rotation during the normal operation of the engine, a starting mechanism therefor including means for rotating 35 both of said portions in unison and subsequently changing the speed of one of said portions with respect to the other to cause the engine to assume its normal cyclic function.
11. In combination, an engine comprising a driving portion and a driven portion adapted for relative rotation during the normal operation of the engine, a starting mechanism therefor including means for rotating 40 both of said portions in unison and subsequently preventing rotation of said driven portion to cause the engine to assume its normal cyclic function.
12. In combination, an engine comprising a driving portion and a driven portion 60 mounted for rotation in unison, means for effecting a change in speed of said driven portion, and means actuated by said driven portion for continuing the rotation of said driving portion in the direction in which it 65 is first moved.
13. In combination, an internal combustion engine having both cylinders and crank shaft adapted for relative rotation during the normal operation of the engine, and 70 starting mechanism therefor comprising means for rotating both the cylinders and crank shaft in unison, and subsequently changing the speed of the crank shaft relative to the cylinders in order to cause the 75 engine to assume its cyclic function.
14. In combination, an internal combustion engine comprising cylinders and a crank shaft adapted for relative rotation with respect to each other during the normal 80 operation of the engine, and starting mechanism therefor including means for rotating both the cylinders and crank shaft in unison, and means for subsequently retarding the rotation of the crank shaft to effect the start- 85 ing of the engine.
15. In combination, a driving mechanism comprising an internal combustion engine mounted for rotation and having a crank shaft mounted to rotate both in unison therewith and in a reverse direction with respect thereto, means for preventing rotation of 90 said shaft to effect a starting of the engine, and means actuated by said shaft for continuing the rotation of the engine in the 95 direction in which it is first moved.
16. The method of starting an internal combustion engine in which a driving and a driven portion are adapted to rotate relative to each other during the normal operation 100 of the engine, which consists in rotating both the driving and driven portions in unison to store energy in the rotating mass, and subsequently retarding the rotation of one of the said portions to permit the stored energy to be utilized in causing the engine to 105 assume its cyclic function.

In testimony whereof I have signed my name to this specification on this 14th day of October, A. D. 1918.

CHARLES Y. KNIGHT.
